US0D1050133S

(12) **United States Design Patent** (10) **Patent No.:** **US D1,050,133 S**
(45) **Date of Patent:** **** Nov. 5, 2024**

(54) **HANDLE OF KEYBOARD HOLDER**

(71) Applicant: **Getac Technology Corporation**, New Taipei (TW)

(72) Inventor: **Shi-Liang Zhong**, Taipei (TW)

(73) Assignee: **Getac Technology Corporation**, New Taipei (TW)

(**) Term: **15 Years**

(21) Appl. No.: **29/862,437**

(22) Filed: **Dec. 8, 2022**

(57) **CLAIM**

The ornamental design for a handle of a keyboard holder as shown and described.

DESCRIPTION

FIG. 1 is a front, top and right side perspective view of a handle of a keyboard holder showing the design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a rear, bottom and left side perspective view of the handle of the keyboard holder.

FIG. 9 is a front view thereof, shown without the keyboard holder for clarity of illustration; and,

FIG. 10 is a bottom view thereof, shown without the keyboard holder for clarity of illustration.

The broken lines in the figures depict portions of the handle of a keyboard holder that form no part of the claimed design. The dot-dashed lines of the keyboard holder in the figures depict environment that forms no part of the claimed design.

1 Claim, 10 Drawing Sheets
